UNITED STATES PATENT OFFICE.

MATILEE IRENE BIXBY, OF NEW YORK, N. Y., ASSIGNOR TO M. LOWENSTEIN & SONS, INC., OF NEW YORK, N. Y., A CORPORATION OF NEW YORK.

DESIGN FOR A TEXTILE FABRIC.

Application filed August 7, 1923. Serial No. 6,971. Term of patent 3½ years.

To all whom it may concern:

Be it known that I, MATILEE IRENE BIXBY, a citizen of the United States, and a resident of the city of New York, borough of Manhattan, in the county and State of New York, United States of America, have invented a new, original, and ornamental Design for a Textile Fabric, of which the following is a specification, reference being had to the accompanying drawing, forming a part thereof.

The figure is a plan view of a piece of textile fabric showing my new design.

I claim:

The ornamental design for a textile fabric, substantially as shown.

MATILEE IRENE BIXBY.
